UNITED STATES PATENT OFFICE.

CRAIG R. ARNOLD, OF PHILADELPHIA, PENNSYLVANIA.

INCANDESCENT ELECTRIC-LAMP SWITCH.

SPECIFICATION forming part of Letters Patent No. 328,831, dated October 20, 1885.

Application filed December 26, 1884. Serial No. 151,265. (No model.)

To all whom it may concern:

Be it known that I, CRAIG R. ARNOLD, a citizen of the United States, residing at Philadelphia, in the county of Philadelphia and 5 State of Pennsylvania, have invented certain new and useful Improvements in Switches for Electric Incandescent Lamps, of which the following is a specification, reference being had therein to the accompanying drawings, where-
10 in—

Figure 1 is a sectional elevation of an electric incandescent lamp and switch mechanism therefor embodying my improvements. Fig. 2 is an elevation of the switch-holder. 15 Fig. 3 is a vertical section of the same. Fig. 4 is a plan of switch and horizontal section of the holder, and Fig. 5 is a horizontal section of the same.

My invention has relation to switching or 20 circuit-connecting devices for electric incandescent lamps; and it has for its object to provide a simple and inexpensive construction of switch of extreme durability.

My invention accordingly consists in the 25 combination, construction, and arrangements of parts as hereinafter described and claimed, having reference particularly to two fixed split or doubled jaw contact-points and a rotary switch so arranged that it makes and 30 breaks circuit without producing undue sparking.

In the drawings, A represents a tubular casing or holder with contracted or other form of neck or bottom a, through which lead the 35 line-wires B B'.

C C' represent spring or other metal clamps, and D D' the contact-points. One of these contact-points is connected to or forms part of clamp C, and the other contact-point is insulated from said clamps, which in turn are insulated from one another. Each contact-point is split or composed of two fingers or jaws, d, which approach or incline toward each other at their outer ends, as more plainly 40 shown in Figs. 4 and 5, and between the jaws of each contact-point rotates the switch E, it being supported upon or fixed to a pintle, e, having a turn-button, e', exterior to the holder A.

50 The wire B' connects with contact-point D,

and wire B with clamp C, as shown, so that when the lamp indicated at F is in the holder A, with the leading wires of the former in contact with the clamps C C', and the switch E bridging or connecting the contacts D D', 55 as illustrated in Fig. 1, the circuit is then by way of wire B, clamp C, to lamp, and from it by way of clamp C', contact D', switch E, contact D, to wire B'.

The inclination of the jaws d of the contact-points insures perfect electrical contact at all times between them and the switch as the impinging surfaces of all of said parts wear.

The switch E being an elongated block, and both its ends e' e" simultaneously making and 65 breaking connections with the contacts D D' in different planes or on different or opposite sides of the same, little or no sparking of the current occurs at the time of forming and severing the contact. Consequently the switch 70 and contacts do not rapidly deteriorate or wear away, as has heretofore been the case with the switches in use.

The switch E may be turned either to the right or left, and, if desired, be provided with 75 suitable stop-pins.

What I claim is—

1. A switch for electric incandescent lamps, comprising a holder or casing, spring-clamps C C', rotating block E, and contact-points D 80 D', each of which is composed of two jaws, d, and one of which is insulated and separate from said clamps, substantially as shown and described.

2. A switch for electric lamps, composed of 85 two tubular clamps insulated from one another, a rotary switch-block, and contact-points, one of which is insulated from said clamps and the other connected to one of the clamps, substantially as shown and described. 9c

3. A switch for electric incandescent lamps, composed of two split or doubled jaw contact-points, a switch-block rotating between the jaws of the contact-points, and metal clamps, one of which is insulated from the 95 contact-points and the other connected to one of said contacts, substantially as shown and described.

4. In a switch for electric incandescent lamps, the contact-points D D', composed of 100

split or double jaws which incline toward each other at their outer ends, substantially as shown and described.

5. The combination of case or holder A, clamps C C', contact-points D D', composed of jaws d, rotary switch E, and wires B B', substantially as shown and described.

In testimony whereof I affix my signature in presence of two witnesses.

CRAIG R. ARNOLD.
